COLUMBIA PLANOGRAPH CO., WASHINGTON, D. C.

UNITED STATES PATENT OFFICE.

WILLIAM H. SHAINLINE AND JOSEPH B. SHAINLINE, OF NORRISTOWN, PENNSYLVANIA.

STEAM-TRAP.

1,164,964.

Specification of Letters Patent. Patented Dec. 21, 1915.

Application filed June 1, 1915. Serial No. 31,447.

To all whom it may concern:

Be it known that we, WILLIAM H. SHAINLINE and JOSEPH B. SHAINLINE, citizens of the United States, residing at 5 Norristown, county of Montgomery, and State of Pennsylvania, have invented certain new and useful Improvements in Steam-Traps, of which the following is a specification.

10 Our invention relates to improvements in steam traps, the object of the invention being to provide a trap of the character stated which will be automatic in its operation, accumulating the water of condensation to 15 a pre-determined level, and then permitting the discharge of the water either to the boiler or to any other point desired.

20 A further object is to provide improved means for automatically controlling the operation of the trap, and in various details 25 of construction which result in a trap which will most efficiently perform the functions for which it is intended.

With these and other objects in view, the 25 invention consists in certain novel features of construction and combinations and arrangements of parts as will be more fully hereinafter described and pointed out in the claims.

30 In the accompanying drawings: Figure 1 is a view in side elevation partly in section illustrating our improved steam trap. Fig. 2 is an end view of Fig. 1. Fig. 3 is a view in transverse section on the staggered line 35 3—3 of Fig. 1. Fig. 4 is an enlarged fragmentary view in section on the line 4—4 of Fig. 1. Fig. 5 is an enlarged view in longitudinal section showing the valve 20 in one position, and Fig. 6 is a similar view 40 of the valve 20 in another position.

1 represents a tank located upon supports 2 on a base plate 3.

4 represents a pipe which is connected with any suitable steam apparatus, and so 45 located as to return the water of condensation to an opening 5 in the bottom of tank 1.

6 is a pipe which we will assume connects the opening 5 with the boiler, although this apparatus may of course be used to direct 50 the water to any other point desired.

The pipes 4 and 6 have check valves 7 and 8 respectively therein which permit a flow in one direction only. While we have illustrated a simple form of check valve, we would have it understood that the invention 55 is not limited in this particular.

9 represents a standard secured to the base plate 3, and having a bearing 10 at its upper end for a lever 11. This lever 11 is angular in form, and is pivoted or fulcrumed between its ends or at the point of the angle as shown clearly in Fig. 1. On one end of the lever 11, a weight 12 is adjustably mounted and secured by a set screw 13. On the other end of the lever 11, a hollow ball 14 is provided, and this ball 14 is connected by a pipe 15 with the top of tank 1, and by a pipe 16 with the bottom of tank 1. Portions of these pipes 15 and 16 are flexible or otherwise constructed so 70 as to permit the movement of the lever without interfering with the communication of the ball with the tank, and cushion stops 17 and 18 are provided on the base 3 to be engaged by the lever 11 and cushion the 75 contact as will be readily understood. A steam supply pipe 19 connects with the top of tank 1, and we will assume that this steam pipe connects with the boiler to which the water in tank 1 is to be returned. In 80 the pipe 19, and constituting a portion thereof, a valve casing 20 is located and supports a turning valve 21. This valve 21 has a relatively large passage 22 therein, and a relatively small passage 23 communicating with the passage 22, and located at right angles to the same. Valve casing 20 has a vent 24 therein through which the steam and air in the tank is adapted to escape when valve 21 is in the position shown 85 in Fig. 5, but which vent is closed when the valve is in the position shown in Fig. 6. We reserve the right to make slight changes in the type of steam valve.

Fig. 1 shows the normal position of the 95 trap. As the water accumulates in the tank 1, it passes upwardly through pipe 16 into the ball 14, and when the water reaches such a level that the ball 14 is filled or partially filled sufficiently to overcome weight 100

12, the lever 11 will move on its pivot 10, so that the ball end of said lever will move downwardly until it engages the cushion stop 18. As soon as the ball begins its downward movement, as it begins to move below the water level in the tank, it will receive an increased quantity of water, so that its downward movement will continue without any interruption. This movement we believe is also facilitated by the shape of the lever as the ball end increases its leverage while it moves downward, while the weight end decreases its leverage as it moves upward. In returning to its set position, the weight end increases its leverage as it moves downward, and the ball end decreases its leverage as it moves upward. As the ball end loses enough water to allow it to start to rise, it also allows more water to drain out of the ball, making it still lighter, therefore, when the lever starts to move in either direction it must continue to the stop.

The valve 20 is provided on its outer end with a crank arm 25 connected by a rod 26 with the ball end of lever 11, so that when the ball moves downwardly, the valve 20 will return to the position shown in Fig. 6, admitting live steam to tank 1 to equalize the pressure with the boiler and allow the water to flow to the boiler from tank 1.

It is to be understood that our improved trap will be located on a higher level than the boiler to which the water is returned, so that as soon as an equilibrium of pressure is established, the water will return to the boiler by gravity.

The operation is as follows: With the trap in set position shown, the valve 20 is in the position shown in Fig. 5, so that as the water accumulates in the tank, the steam or air in the upper portion of the tank is allowed to escape through vent 24. When the water reaches a level in the tank and in the ball 14 to overcome weight 12, the lever will move on its pivot 10 until the ball end of lever 11 is stopped by the cushion stop 18. This downward movement of the ball end of the lever will move valve 21 to the position shown in Fig. 6, admitting live steam to the tank, establishing an equilibrium with the boiler and allowing the water in the tank to escape past check valve 8 and through pipe 6 to the boiler. When the level of water in the tank falls below the desired level so as to drain the ball 14 and lighten this end of the lever, weight 12 will operate to return the parts to normal set position as above described. The operation is therefore entirely automatic and all forms of packing are dispensed with. Suitable pipe openings can be made in the tank so that the trap can be used as a return trap, a non-return trap, a vacuum trap, or a condenser trap, and all openings not needed in

the particular case can be plugged, therefore, we have one design of trap which can be connected as either kind.

Various slight changes might be made in the general form and arrangement of parts described without departing from our invention, and hence we do not limit ourselves to the precise details set forth, but consider ourselves at liberty to make such changes and alterations as fairly fall within the spirit and scope of the appended claims.

Having thus described our invention, what we claim as new and desire to secure by Letters Patent is:

1. The combination with a tank, a pipe directing water into the bottom of the tank, an outlet pipe for water communicating with the bottom of the tank, and check valves controlling the flow of water through said pipe, of a steam pipe communicating with the upper portion of the tank, a standard, an angular lever pivotally connected between its ends to the standard, one end of the lever normally elevated above the other end, an adjustable weight on one end of the lever, a hollow ball at the elevated end of the lever, flexible pipes connecting the ball with the upper and lower portions of the tank, a valve in the steam pipe, means connecting the valve with one end of the angular lever, and means for limiting the pivotal movement of the lever, substantially as described.

2. The combination with a tank, a pipe directing water into the bottom of the tank, an outlet pipe for water communicating with the bottom of the tank, and check valves controlling the flow of water through said pipe, of a steam pipe communicating with the upper portion of the tank, a standard, an angular lever pivotally connected between its ends to the standard, one end of the lever normally elevated above the other end, an adjustable weight on one end of the lever, a hollow ball at the elevated end of the lever, flexible pipes connecting the ball with the upper and lower portions of the tank, a valve in the steam pipe, means connecting the valve with one end of the angular lever, and cushion stops located under the lever at opposite sides of its pivot, and limiting the movement of the lever in both directions, substantially as described.

3. The combination with a tank, and valved inlet and outlet pipes communicating with the bottom of the tank, of a steam pipe communicating with the upper portion of the tank, a standard independent of the tank, an angular lever pivotally connected at its angle to the standard, an adjustable weight on one end of the lever, a hollow ball at the other end of the lever normally located in a plane above the weight, flexible

pipes connecting the ball with the upper and lower portions of the tank, a valve in the steam pipe, means connecting the valve with one end of the angular lever, and means limiting the movement of the lever in both directions, substantially as described.

In testimony whereof we have signed our

names to this specification in the presence of two subscribing witnesses.
